UNITED STATES PATENT OFFICE.

LEWIS NEUENSCHWANDER, OF LOS ANGELES, CALIFORNIA, ASSIGNOR TO ELECTRIC FRUIT MARKING CO., OF LOS ANGELES, CALIFORNIA, A CORPORATION OF CALIFORNIA.

INKING DEVICE FOR MARKING MACHINES.

Application filed August 29, 1921. Serial No. 496,206.

To all whom it may concern:

Be it known that I, LEWIS NEUENSCHWANDER, a citizen of the United States of America, and a resident of the city of Los Angeles, county of Los Angeles, and State of California, have invented a new and useful Ink- 5 ing Device for Marking Machines, of which the following is a specification.

My invention relates to apparatus for inking dies.

The broad object of my invention is to provide improved means for inking the marking dies of my electric fruit marking machine which is the subject of my copending application Serial Number 451,780.

The invention possesses other features of advantage, some of which, with the foregoing, will be set forth in the following description of the preferred form of my invention which is illustrated in the drawings accompanying and forming a part of the specification. It is to be understood that I do not limit myself to the showing made by the said drawings and description, as I may adopt variations of the preferred form within the scope of my invention as set forth in the claims.

Referring to the drawing: Fig. 1 is a front elevation of a portion of the machine in which my inking device is incorporated. Fig. 2 is a vertical sectional view of a portion of the machine, the plane of section being indicated by the line 2—2 of Fig. 1. Fig. 3 is a side elevation in a larger scale of the inking pad arm, and die wheel. The plane in which the view is taken is indicated by the line 3—3 of Fig. 1.

A quadruple marking machine is shown in the drawings, that is, one in which there are four sets of dies with inking means for all, so that four pieces of fruit are marked simultaneously. Parts of the machine not directly related to the present invention are omitted. It is of course obvious that the inking device may be built for any desired number of dies.

Journalled in bearings arranged in the vertical frame members 2 and 3 is a die shaft 4. Annular flanges 6 are arranged on the shaft, and dies 7 are attached to the periphery of the flanges.

Means are provided for rotating the die shaft intermittently to present the dies on each flange successively at a predetermined

operating station where they remain fixed 55 for a moment while the fruit passes over them. The outer end of the die shaft at one side of the machine is connected by Geneva gears with cam shaft 11, driven by suitable gearing 8 connecting it with the pulley 21 driven by belt from any suitable source of power. With each full revolution of the shaft 11 the die shaft is turned thru one step of its intermittent motion and then held stationary for a moment.

Arranged on the frame of the machine is a table 22 over which the fruit passes as it is being marked. The table is formed with ridges 23 dividing it into troughs extending across the top of each die wheel. The bottom of the trough is cut away over the dies, so that when the die wheel rotates, each die successively moves upwardly into the trough and comes to rest with its face projecting a small amount above the bottom, so that each piece of fruit rolling through the trough contacts with the die and is marked. Means are provided for feeding a succession of pieces of fruit upon the table and across the die wheel and in the intervals between the arrival of the pieces over the die wheel it is turned to bring a fresh die into the operating position.

Means are provided for inking the dies. Mounted on the lower portion of the frame 85 of the machine are two spools 26 and 27 adapted to contain an inking ribbon 28 which is led over guide rollers 29 and under the die shaft below the dies. Rotatably mounted on the shaft 31 are a series of pad arms 32, one extending out below each die flange. Mounted in each arm 32 is a roller 33 engaged by a cam 34 fixed on the shaft 11. Each roller 33 is resiliently retained 90 against its cam by a torsion spring 36, interposed between the hub of the arm 32 and the collar 37 adjustably fixed on the shaft 31. Thus, with rotation of shaft 11 the pad arms are rocked, the springs 36 raising the ends of the pad arms to press the ribbon against the die then directly above the ribbon, and after a momentary contact the cam forces the pad arm down. The timing of the cams is such that the contact of the ribbon with the dies is effected during the periods of rest of the die shaft and it will be seen that each die is freshly inked for each contact with the fruit.

In order to insure even inking of the

die, the end of each pad arm is provided with a pad 38, preferably made of conformable material such as composition cork, held in the channel 39 which is resiliently 5 mounted on the plate 41 by means of studs 42 surrounded by springs 43. The plate is removably connected to the pad arm by a thumb screw 44. Thus the resiliently mounted pad evenly presses the ribbon upon 10 the whole surface of the die irrespective of small defects in alignment of the parts.

The spools 26 and 27 are each mounted on a shaft 45 near the other end of which is rotatably mounted a worm wheel 46 engaging a worm 47 on the shaft 48, which is driven by gears 49 driven by gearing 8. One of the worms 47 is right hand and one 15 left hand. A pin clutch 51 disposed on each spool shaft provides means for coupling the spool shaft to the associated worm wheel. The clutches are controlled by yokes 52 on the ends of lever 53 pivoted at its center on the frame of the machine and provided with a handle 54 wherewith one or 20 the other of the clutches may be engaged, so that the ribbon may be fed in either direction. The ribbon is fed very slowly 25 across the pad arms and is long enough for a day's run, so that only an occasional 30 shifting of the clutches is required.

While I have herein described my inking device as embodied in a fruit marking machine, it is to be understood that it may 35 be applied to dies in machines for marking other articles.

I claim:

1. The combination with a plurality of dies successively movable to a fixed operative position of an inking ribbon, fixed supports 40 for holding said ribbon adjacent said dies, and means for pressing the ribbon against each die before it moves to said operative position.

2. The combination with a plurality of 45 dies successively movable to a fixed operative position of an inking ribbon, spools journaled on fixed axes for holding said ribbon adjacent said dies, and a resiliently mounted pad for pressing the ribbon 50 against each die before it moves to said operative position.

3. In combination, a plurality of dies 55 successively movable from inoperative to operative position, an inking ribbon, rollers journaled on fixed axes for guiding said ribbon in position adjacent said dies in their inoperative position, means for pressing the ribbon against each die in its inoperative position to ink the die, and means 60 for feeding said ribbon past said dies and

for moving the inked die to operative position.

4. The combination with a plurality of dies successively movable to a fixed operative position of an inking ribbon arranged 65 adjacent said dies, means for pressing the ribbon against each die before it moves to said operative position, means for feeding said ribbon past said dies, and manually operated means for reversing the direction 70 of said feeding.

5. In combination, a plurality of dies successively movable to a fixed operative position, an inking ribbon arranged adjacent said dies, a spring pressed arm adapted 75 to engage the side of said ribbon opposite the dies, and a cam acting in time with the movement of said dies for moving said arm whereby the ribbon is pressed against each die before it moves to operative position.

6. The combination with a plurality of dies successively movable to a fixed operative position of an inking ribbon arranged adjacent said dies, a spring-pressed arm extending adjacent the opposite side of said ribbon, a pad of conformable material 80 resiliently arranged on said arm, and a cam acting in time with the movement of said dies for moving said arm whereby the ribbon is pressed against each die by said pad before it moves to operative position.

7. In combination, a plurality of dies successively movable to a fixed operative position, an inking ribbon arranged adjacent said dies, a spring pressed arm adapted 95 to engage the side of said ribbon opposite the dies, a cam acting in time with the movement of said dies for moving said arm whereby the ribbon is pressed against each die before it moves to operative position, and means for feeding said ribbon past said dies.

8. The combination with a plurality of dies successively movable to a fixed operative position of an inking ribbon arranged adjacent said dies, a spring-pressed arm extending adjacent the opposite side of said ribbon, a pad of conformable material 100 resiliently arranged on said arm, a cam acting in time with the movement of said dies for moving said arm whereby the ribbon is pressed against each die before it moves to operative position, and means for feeding said ribbon in either direction 105 past said dies.

In testimony whereof, I have hereunto set my hand.

LEWIS NEUENSCHWANDER.
